UNITED STATES PATENT OFFICE.

ISRAEL BUTLER, OF BUFFALO, NEW YORK, ASSIGNOR OF ONE-HALF TO JAMES I. BRUNSON AND GRIFFIN A. SAUNDERS.

TRAIN CONTROL.

1,414,860.

Specification of Letters Patent. Patented May 2, 1922.

Application filed February 14, 1921, Serial No 444,808. Renewed March 8, 1922. Serial No. 542,167.

To all whom it may concern:

Be it known that I, ISRAEL BUTLER, a citizen of the United States, residing at Buffalo, in the county of Erie and State of New York, have invented new and useful Improvements in Train Controls, of which the following is a specification.

This invention relates to improvements in automatically operated train control apparatus and has for an object the provision of electrically operated means controlled by the position of the signal of a block signal system for automatically cutting off the power of a locomotive and applying the brakes, in the event of the signal being set against the train.

Another object of the invention is the provision of an electrically operated train control apparatus in which the brakes are applied for a limited period of time to check the progress of the train and then quickly released, the brakes being thereafter again applied to bring the train to a full stop. This eliminates danger of derailing or otherwise wrecking the train by a quick and sudden stop.

With the above and other objects in view, the invention further includes the following novel features and details of construction, to be hereinafter more fully described, illustrated in the accompanying drawings and pointed out in the appended claims.

In the drawings:

Figure 1 is a diagrammatic view showing the connections between the track devices and the train carried devices.

Figure 2 is a side elevation of a portion of a locomotive, the latter being partly broken away to more clearly show the invention.

Figure 3 is a detail elevation of the operating motors and showing in section the connections of these motors with the throttle lever and engineer's brake valve.

Figure 4 is a sectional view on the line 4-4 of Figure 3.

Figure 5 is a view looking at the end of the throttle lever, showing the means for releasing the throttle lever latch.

Figure 6 is an elevation of the device shown in Figure 5.

Figure 7 is a detail view of the contact shoes.

Referring specifically to the drawings, wherein like characters of reference denote

corresponding parts, the reference character 10 indicates a bracket or support which is adapted to be positioned upon one side of the boiler of a locomotive, preferably, upon the left hand side of the cab. Supported in this bracket is a motor 11, whose shaft 12 has secured thereon a pinion 13, which is engaged by a rack bar 14, the latter being mounted for sliding movement within a guide 15. One end of the rack bar 14 has 60 pivotally connected thereto as indicated at 16, a rack bar 17, which is mounted for sliding movement in a frame 18, the latter being secured to the handle of the throttle lever L, as shown at 19. Extending inwardly 70 from the frame 18, is an arm 20, to which is rotatably secured a sector 21, which is engaged by the rack bar 17. The sector 21 is provided with an arm 22, so arranged that when the sector is rotated through the 75 action of the rack bar 17, this arm 22 will engage the operating handle H which controls the latch of the throttle lever L and release said latch. The initial movement of the rack bar 17 will therefore release the 80 throttle lever, while a further movement will operate the said lever to reduce or cut off the power.

Also mounted in the bracket 10 are additional motors 23 and 24, the said motors 85 being arranged side by side in spaced relation and having their shafts 25 coupled together in alignment by means of a coupling member 26. Mounted upon this coupling member is a pinion 27, which engages the 90 rack bar 28, the latter being mounted for sliding movement in a guide 29 and having connected thereto at one end as shown at 30, a lever 31. This last mentioned lever is connected to the engineer's brake valve B, so 95 that the operation of either the motor 23 or 24 will operate the engineer's brake valve, to either apply or release the brakes, depending upon which motor is operated. Each of the rack bars 14 and 28 have their guides 15 100 and 29 respectively resting upon supports 32, the latter being connected to the bracket 10.

All of the above mentioned mechanism is mounted in the cab of the locomotive, and in addition, the locomotive carries a plurality of contact shoes which are indicated at 33, 34 and 35 and which are respectively connected to the motors 11, 23 and 24.

Positioned alongside of the rails R of the track, are ramp rails 36, 37 38 and 39, the 110

rail 36 being in the path of and adapted to be engaged by the shoe 33, while the rails 37 and 39 are in the path of and engaged by the shoe 34. The rail 38 is positioned so as 5 to be engaged by the shoe 35.

The locomotive shoes are arranged in pairs, that is, the shoe 33 forms one of a pair of shoes, the other shoe being indicated at 10 33', while the shoes 34 and 35 respectively are arranged with shoes 34' and 35'. The 15 shoes are spaced apart as shown in the drawings and the ramp rails are also arranged in pairs and spaced apart, the rails 36, 37, 38 and 39 being arranged in pairs with the 15 rails 36', 37', 38', and 39' respectively.

This is clearly illustrated in Figure 1 of the drawings and in this figure there is shown the source of current for example, batteries B'. Extending from one pole of 20 these batteries is a conductor 40, which connects with the motor 24, while a conductor 41 tapped on to the conductor 40 connects the source of current with the motor 23. An additional conductor 42 tapped on to the conductor 40 connects with the motor 11. The last named motor is connected to the shoe 33' by a conductor 43, while the shoe 33 is connected by a conductor 44 with the opposite side of the battery B, this connection 30 being effected through a conductor 45 which connects the battery with the shoe 35. A conductor 46 connects the motor 23 with the shoe 34' and the shoe 34 is connected to the battery B by a conductor 47 which is tapped 35 on to the conductor 45. The motor 24 is connected to the shoe 35' by a conductor 48.

The circuits of the ramp rails include conductors 49, 50 and 51, the ramp rails being duplicated upon opposite sides of a signal 40 52, which is controlled by the block signal system so that the invention will be operated by a train traveling in either direction. The ramp rails for a train traveling in one direction are connected in parallel with the conductors 50 and 51 by means of conductors 45 53, 54, 55, 56, while the ramp rails which would be engaged by the shoes of a train traveling in an opposite direction are connected in parallel between the conductors 49 50 and 50, by conductors 53', 54', 55' and 56', while the conductors 49 and 51 are connected as shown at 57.

In the operation of the invention, a train approaching a signal set at danger will have 55 the motor 11 operated to cut off steam by contact of the shoes 33 and 33' with the ramp rails 36 and 36'. Current will then flow from one side of the battery B' through the conductor 42, the motor 11, the conductor 43, the shoe 33', the ramp rail 36', the conductor 53, the conductor 50 and through a conductor 58 which bridges the conductors 49 and 50 and which is connected to spaced 60 contacts 59, the latter having been bridged 65 when the signal 52 was set at danger. Cur-

rent will then flow through the conductor 49, the conductor 57, the conductor 50, the ramp rail 36, the shoe 33, the conductor 44 back to the opposite side of the battery B'. After the steam has been cut off, a further 70 forward movement of the train in the direction of the arrow shown in Figure 1 will cause the shoes 34 and 34' to engage the ramp rails 37 and 37', whereupon current 75 will flow from one side of the battery B' through the conductor 41, the motor 23, the conductor 46, the shoe 34', the ramp rail 37', the conductor 54, the conductor 50, the conductor 58, the conductor 49, the conductor 57, the conductor 50, the rail 37, the conductor 34', the conductor 47 back to the opposite side of the battery B'. This will 80 operate the motor 23 to apply the brakes, but this application will be only momentary, as before the train can be brought to a full stop, 85 the contacts 35 and 35' will engage the ramp rails 38 and 38' so as to close the circuit through the motor 24 and operate the rack bar 38 in an opposite direction and release the brakes. This permits the train to proceed 90 under reduced headway until the contact shoes 34 and 34' engage the ramp rails 39 and 39', whereupon the circuit of the motor 23 will be again completed and this motor operated to move the rack bar 28 95 in a reverse direction from that caused by the motor 24, so that the brakes will be again applied and the train brought to a full stop.

The invention is susceptible of various changes in its form, proportions and minor 100 details of construction and the right is herein reserved to make such changes as properly fall within the scope of the appended claims.

Having described the invention what is 105 claimed is:

1. The combination with a railway electric block signal system, of a motor for cutting off the power of the train, a motor for applying the brakes, a motor for releasing the brakes, means controlled by the signal for successively operating the motors and means whereby the brake applying motor will be again operated to stop the train after the operation of the brake releasing motor. 110

2. The combination with a railway electric block signal system, of a motor for cutting off the power of the train, means including a toothed segment for connecting the motor with the throttle, a motor for applying the brakes, a motor for releasing the brakes and means controlled by the signal for successively operating the motors and means whereby the brake applying motor will be again operated to stop the train after 120 the operation of the brake releasing motor. 125

3. The combination with a railway electric block signal system, of a motor for applying the brakes, a motor for releasing the brakes, the two last mentioned motors hav- 130

ing their shafts coupled in alignment and arranged to rotate in opposite directions, means controlled by the signal for successively operating the motors and means whereby the brake applying motor will be again operated to stop the train after the operation of the brake releasing motor.

4. The combination with a railway electric block signal system, of a horizontally movable brake controlling arm located within the cab of a locomotive and connected to the engineer's brake valve, electrically operated means for operating the brake controlling arm and means controlled by the block signal system and including a plurality of train carried contact shoes arranged

in pairs for operating the arm and successively applying the brakes, then releasing the same and again applying them.

5. The combination with a railway electric block signal system, of means controlled by said signal to successively shut off the power of the train, apply the brakes, release the latter and again apply the brakes to stop the train and a rotatably mounted throttle latch engaging arm operated by the power controlling means to release the throttle lever and permit of the operation of the latter.

In testimony whereof I affix my signature.

ISRAEL BUTLER.
